VALVE FOR ROCK DRILLS

Filed Dec. 1, 1926

FIG. - 1.

FIG. - 2.

INVENTOR.
William A. Smith Jr.

BY *Herb G. Oden*
HIS ATTORNEY.

UNITED STATES PATENT OFFICE.

WILLIAM A. SMITH, JR., OF NEW YORK, N. Y., ASSIGNOR TO INGERSOLL-RAND COMPANY, OF JERSEY CITY, NEW JERSEY, A CORPORATION OF NEW JERSEY.

VALVE FOR ROCK DRILLS.

Application filed December 1, 1926. Serial No. 151,954.

This invention relates to rock drills, but more particularly to a distributing valve for fluid actuated rock drills of the hammer type.

5 The objects of the invention are to lighten the valve, to simplify the construction of valves of this type, and to obtain a quick and positive valve action.

10 Other objects will appear hereinafter.

10 The invention consists of the features of construction and arrangement of parts substantially as hereinafter described and claimed and illustrated in the accompanying drawings, in which

15 Figure 1 is a sectional elevation of a portion of a rock drill showing the valve in one of its limiting positions, and

20 Figure 2 is a view similar to Figure 1, showing the valve in its other limiting position.

25 Referring to the drawings, A represents a cylinder having a reciprocating hammer piston B. A drill steel C projects into the front end of the cylinder A to receive the blows of the hammer piston B and is guided by a head D which forms a closure for the front end of the cylinder.

At the rearward end of the cylinder A is disposed a valve chest designated generally 0 by E. The valve chest E in this instance comprises a valve block F and front and rear plates G and H respectively. The front plate G interposed in this instance between the valve block F and the cylinder A has a 5 rearwardly extending boss J which fits into a recess K in the front end of the valve block F for the purpose of centralizing the valve block and the plate G with respect to each other. In the present instance the plate G also acts as a closure for the rearward end 10 of the cylinder.

In the valve block F is formed a valve chamber L closed at its front end by the plate G and having an enlarged bore O at its rearward end into which extends a projection P carried by the plate H for holding the said plate H in proper assembled relationship with respect to the valve block F.

Pressure fluid conveyed from any suitable source of supply (not shown) may be delivered to a passage Q in a back head R, and the distribution of such pressure fluid is effected by a distributing valve S having in this instance a bore T of uniform diameter

throughout its length in constant communication with the pressure fluid supply.

At the rearward end of the valve is formed an actuating surface U which is constantly exposed to pressure fluid for throwing the valve in a forwardly direction 60 and an annular actuating face V of larger area than the surface U is formed at the front end of the valve to be intermittently exposed to pressure for throwing the valve rearwardly. In the present instance the valve S carries a flange W near its rearward end and the rearward face X of said flange constitutes an actuating face against which pressure fluid may intermittently act to assist the pressure fluid acting against the surface U for throwing the valve S forwardly.

Communication between the front end of the valve chamber L and the rearward end of the cylinder A is afforded by a plurality of inlet passages Y through the boss J of 76 the plate G, and pressure fluid to the front end of the cylinder A is conveyed thereto through a passage Z in the cylinder A, the plate G and the valve block F, said passage Z communicating with the rearward end of the valve chamber L through a port b in the valve block F. The passage Z also serves as an exhaust passage for the pressure fluid from the front end of the cylinder A and communicates with the enlarged bore O 85 through a port c controlled by the flange W.

Leading from a point near the rearward end of the cylinder A is an exhaust passage d which leads to an annular port e near the front end of the valve chamber L for exhausting the pressure fluid from the rearward end of the cylinder. The port e in the present instance is controlled by a flange f formed on the front end of the valve S. It will be noted that the pressure fluid from

both ends of the cylinder A is exhausted to the valve chamber and such exhaust of pressure fluid may pass therefrom to the atmosphere through an exhaust port g located between the port e and the enlarged bore O of 100 the valve chamber.

In order to convey live pressure fluid from the cylinder A to the rearward end of the enlarged bore O to act against the actuating face X, a passage h is formed in the cylinder A and the valve block F and is controlled only by the piston B. Such pressure fluid may be exhausted from the rearward end of

the enlarged bore O through an exhaust passage j in the valve block F controlled by the flange W of the valve. Preferably a small conduit k is formed through the boss J of the plate G to permit a constant restricted flow of pressure fluid from the valve chamber into the rearward end of the cylinder A.

In the operation of the drill with the parts in the positions illustrated in Figure 1, 10 pressure fluid entering the passage Q will flow through the valve S and through the front end of the chamber L and the inlet passages Y into the rearward end of the cylinder A to impel the piston B forwardly 15 against the drill steel.

Slightly prior to the instant of delivery of the blow against the drill steel the passage h will be uncovered by the piston B and pressure fluid will then flow through said passage 20 sage h to the rearward end of the bore O and acting against the actuating face X will augment the pressure fluid acting against the actuating surface U to throw the valve S forwardly to the position shown in Figure 2.

25 As the valve is thrown forwardly the flange f will uncover the port e thus providing an escape for the pressure fluid in the rearward end of the cylinder through the passage d, the port e and thence through the exhaust 30 port g to the atmosphere.

With the valve thrown forwardly pressure fluid will flow over the rearward end of the valve through the port b, thence through the inlet passage Z to the front end 35 of the cylinder to drive the piston B rearwardly.

During a portion of the rearward stroke of the piston B the atmospheric air together with the pressure fluid leaking into the rearward end of the cylinder through the conduit k will be expelled through the passage d and the exhaust port to the atmosphere. 40 However, after the piston B overruns the passage d the air will be compressed in the rearward end of the cylinder by the piston 45 and acting against the actuating surface V will again throw the valve rearwardly to its initial position, thus completing the cycle of operations.

50 I claim:

1. In a fluid actuated rock drill, the combination of a cylinder, a hammer piston in the cylinder, a valve chest having a valve

chamber closed at its front end, inlet passages leading from the valve chamber to the cylinder, a valve in the valve chamber having a bore therethrough, said bore being in constant communication with a source of pressure fluid supply, an actuating surface on the rearward end of the valve constantly exposed to live pressure fluid for throwing the valve forwardly, a flange on the valve having an actuating surface intermittently exposed to live pressure fluid to assist in throwing the valve forwardly, said flange 65 controlling the exhaust of fluid from the front end of the cylinder, an annular actuating surface at the front end of the valve intermittently exposed to air compressed by the piston for throwing the valve rearwardly, 70 and a passage in the cylinder and the valve chest for conveying pressure fluid to the actuating face on the flange, said passage being controlled only by the piston.

2. In a fluid actuated rock drill, the combination of a cylinder, a hammer piston in the cylinder, a valve chest having a valve chamber, front and rear inlet passages leading from the valve chamber to the cylinder, an exhaust passage leading from the valve chamber to the atmosphere, a valve controlling the inlet and exhaust passages, said valve being hollow to convey pressure fluid therethrough to the rear inlet passage, a rear actuating surface on the valve constantly exposed to pressure fluid for throwing the valve forwardly, a flange near the rearward end of the valve having an actuating face intermittently exposed to pressure fluid to assist in throwing the valve forwardly, an actuating surface at the front end of the valve intermittently exposed to air compressed by the piston for throwing the valve rearwardly, a kicker passage in the cylinder and valve chest for conveying pressure fluid from the cylinder to the actuating surface on the flange, said kicker passage being controlled by the piston, and a passage in the end of the valve chest constantly admitting pressure fluid to the rearward end of the cylinder to augment the compression for throwing the valve rearwardly.

In testimony whereof I have signed this specification.

WILLIAM A. SMITH, JR.
